UNITED STATES PATENT OFFICE.

HARVEY C. LOWRIE, OF NEW YORK, N. Y.

WALL SAFE OR RECEPTACLE.

No. 873,878.

Specification of Letters Patent.

Patented Dec. 17, 1907.

Application filed September 26, 1906. Serial No. 336,300.

To all whom it may concern:

Be it known that I, HARVEY C. LOWRIE, a citizen of the United States, residing at New York, in the county of New York and State 5 of New York, have invented new and useful Improvements in Wall Safes or Receptacles, of which the following is a specification.

My invention relates to a wall safe or receptacle, such, for instance, as is illustrated 10 in United States Letters Patent No. 711,326, granted to me October 14, 1902.

As heretofore constructed, safes or receptacles designed to be built or embedded in a brick or other wall, are provided with a door 15 and door-casing which are designed to be substantially flush with the interior surface of the finished wall, the main or body portion of the receptacle being completely surrounded by masonry and plaster, so that the door and 20 door-casing form the only exposed portions of the safe. Safes of this character are placed in the walls of office buildings and apartment houses for the individual use of the occupants of the offices or apartments, 25 and are usually placed in the walls during the construction of the buildings. The workmen in setting the safes in the walls are required to exercise considerable care in adjusting them so that the door and casing will 30 be in alignment with the interior surface of the plaster which is to form the interior finish; and however accurately the safe may have been adjusted in the first instance, it is necessary for the workmen who apply 35 the plaster to work up to the door casing with considerable care in order to effect a neat and unobjectionable finish. It is also important that the exposed portions of the safe, i. e. the door and door-casing, be protected as far as possible from injury during 40 building operations, and for this purpose temporary sheet-metal covers have been placed over the door and casing, to be removed after the building is completed and 45 the safe ready for use. But this sheet-metal cover has not prevented corrosion of polished metal surfaces, and as said cover is easily removed, the working parts of the safe lock are liable to be injured by persons whose 50 curiosity may lead them to attempt to open and examine the construction and mode of operation.

The main object of my invention is to provide a safe which may be constructed at less 55 cost and built into a wall with less trouble than the old form of safe, and with abso-

lutely no liability of injury to the door and door-casing, and which when built into a wall will present a finish in accordance with the best architectural requirements. 60

Briefly stated my invention consists in constructing the receptacle and door-casing in such a manner that the casing may be secured to the receptacle after the latter has been completely embedded in a wall; and in 65 providing the receptacle with a temporary cover or closure, which, in addition to protecting the interior of the receptacle, serves as a guide to the workmen in initially setting the safe in a wall, also as a guide to the plasterers 70 in finishing the wall, and which also serves as a core for forming an opening in the plaster for receiving the permanent door-casing.

By making the door-casing a separate part of the safe structure, to be applied after 75 the receptacle has been built into a wall and the latter completely finished, there is a material saving in cost of manufacture, and hurried orders for safes may be more quickly filled. The receptacles are single integral 80 castings which require little or no machining, and these can be quickly made and supplied to builders, and the door-casings and doors constructed at some future time to be applied to the safes only when required for 85 use.

To more particularly describe my invention, I will refer to the accompanying drawings in which

Figure 1 is a front elevation of a safe or receptacle constructed in accordance with my invention. Fig. 2 is a vertical central section of the same with my temporary cover applied thereto, said figure also showing a section of a brick wall in which the safe or 90 receptacle is built. Fig. 3 is a front view of a permanent door-casing which is applied to the receptacle after the temporary cover is removed, and Fig. 4 is a central vertical section through the safe opening, showing 95 the permanent door-casing applied thereto.

The safe or receptacle A, illustrated in Fig. 1, is preferably made in a single integral casting of iron or other suitable material, and none of its surfaces need be machined or finished to adapt it for use, but it is usual and desirable to coat the interior with white enamel or some other suitable covering to give it a clean and attractive appearance. The size and shape of the receptacle may be made to suit particular requirements, and when desired, it may be 105 110

provided with suitable means for anchoring it in the wall in which it is to be built. The receptacle illustrated is rectangular in form, and is provided with perforated lugs *a* which receive anchoring rods *a'*, as shown and described in the Letters Patent hereinbefore referred to. The front wall of the receptacle is provided with a circular opening *B*, the surrounding wall of which is stepped to form a seat *b* for the permanent door casing. Around the opening *B*, and within that portion of the surrounding wall of the opening which constitutes the seat *b*, is a series of holes *b'* which receive the bolts which lock the door-casing to the receptacle.

As hereinbefore indicated, it is not necessary to machine or finish any part of the receptacle beyond giving to the interior a coating of enamel or such other finish as may be thought desirable; and when the opening *B* is closed by a temporary cover, such as will be presently described, the receptacle is ready to be placed in the wall for which it is designed.

The temporary cover *C*, as illustrated in Fig. 2, consists of two circular blocks *c* and *c'*, preferably made of wood. The inner block *c* is made to fit the seat *b* which surrounds the safe opening, though it is not necessary that said block be accurately formed, and if it be sawed from a board of suitable thickness, it will serve the purpose. Its thickness should be equal to or slightly less than the depth of the seat *b*, so that the outer surface of the block will be flush with, or a little inside of the outer face of the wall immediately surrounding the opening. This block *c* is secured to the receptacle by means of two or more screws *d*, each of which passes through said block into one of the holes *b'* which are provided for the door-casing screws to be hereinafter referred to, the two or more holes *b'* which are to receive said screws *d* being threaded to engage therewith, as shown in Fig. 2. The outer block *c'* is made larger than the block *c* in order that it may slightly overlap the edge of the safe opening and thus securely close the same against the entrance of dirt, dust and moisture from wet plaster. The block *c'* is secured to the block *c* by means of screws *d'* which also serve as the means for tightly clamping the block against the wall of the safe to close the opening, as will be readily understood. The block *c'* should project sufficiently beyond the front wall of the safe to afford a surface *c*² which will be in line with the interior surface of the finished wall in which the safe is to be built; and said block is tapered from the front to the rear surface, as at *c*³, in order that it may be readily withdrawn from the plaster which is to surround the block, and in which the block is to form a circular opening for the reception of the permanent door-casing.

The two blocks *c* and *c'* could be formed integrally from a single block of wood, but as this would add to the cost, I prefer to form them separately as shown.

When the safe is initially set in a wall, such as is shown at *E* in Fig. 2, it is so adjusted that the outer surface *c*² of the temporary cover *C* will be in line with the surface of the plaster which is to be afterwards applied to the wall to form the interior finish, the surface of the plaster being indicated by the dotted line *e*, Fig. 2. When the plaster is being applied, the temporary cover offers no obstruction to the proper handling of the plasterer's trowel, and all that is necessary is to simply finish the wall flush with the surface *c*² of the temporary cover, using said surface as a "ground" in a manner familiar to plasterers. When the plaster is dry, the cover may be readily removed so as to leave a smooth circular opening. If the wall is to be papered, the paper may be laid over the temporary cover, and when the latter is to be removed the paper may be cut around the edge of the block *c'*, and after scraping the paper from the cover at the points occupied by the screws *d'*, the latter may be withdrawn and the block *c'* removed. To remove the block *c* it is only necessary to remove the screws *d* when said block may be removed by means of the finger-hole *c*⁴ which is provided for that purpose.

In order that the temporary cover may be accurately located after the wall has been covered with paper, the block *c'* is provided with a central stud or pin *f* which will project through the paper sufficiently to show the location of the cover and which will also serve as a center in inscribing a circle to serve as a guide in cutting the paper approximately in line with the edge of the block *c'*, so that the latter may be removed without injury to the surrounding finish of the wall.

The permanent door-casing which is to be applied to the receptacle after the temporary cover is removed, consists of a ring-like structure which is made to fit the seat *b* provided for it around the receptacle opening. The permanent casing *G*, illustrated in Figs. 3 and 4, is provided with threaded screw holes *g* corresponding in number and in location to the holes *b*¹ in the casing seat, said threaded holes being located in an annular shoulder *g'* which fits into the receptacle opening, and which is drawn towards the seat *b* by screws *h*, the latter passing through the holes *b'* and screwing into the holes in the casing for securely holding and locking the latter to the receptacle, as clearly shown in Fig. 4.

The outer edge of the casing *G* is provided with an annular flange or projection *g*² which overlaps the edge of the opening in the plaster *e'*, which was formed by the temporary cover, as clearly shown in Fig. 4, and as said

casing is made of proper dimensions to permit it to properly seat itself in said opening, it will be readily seen that the casing may be adjusted to the surface of the plaster and 5 securely locked to the receptacle in such a manner as to provide for a neater and more perfect finish than is possible with the old form of construction.

The door-casing which has been selected 10 for illustration is designed to receive a circular door, (not shown,) which is provided with suitable lugs or projections adapted to engage with the lugs g^3 shown on the interior of the casing, but as said door forms no part 15 of my present invention, it needs no particular description.

Having thus described my invention, what I claim as new and desire to secure by Letters Patent is,

20 1. The combination with a wall safe or receptacle having an opening adapted to receive a permanent door-casing, of a temporary cover closing said opening and projecting beyond the wall of the safe for the 25 purpose specified.

2. The combination with a wall safe or receptacle having an opening adapted to receive a permanent door-casing, of a temporary cover having an inwardly tapering 30 projection beyond the wall of the safe to serve as a core for forming an opening in the plaster of the wall in which the safe is to be built.

3. The combination with a wall safe or receptacle having a circular opening, the surrounding wall of the opening being stepped to form a seat for a permanent door-casing, of a temporary cover closing said opening, said cover comprising two circular blocks, 35 one of which occupies the seat surrounding the opening, and the other of which is secured to the first mentioned block to form a circular projection beyond the wall of the safe.

4. The combination with a wall safe or receptacle having a circular opening the surrounding wall of which is provided with a seat for a permanent door-casing, of a tem- 40

porary cover closing said opening, said cover comprising two circular blocks differing in size, the smaller block occupying the seat 50 around said opening, and the larger block being secured to the smaller block with its outer edge covering the edge of said opening.

5. The combination with a wall safe or receptacle having an opening adapted to receive a door-casing, of a temporary cover closing said opening, said cover being provided with a pin or stud projecting centrally therefrom, for the purpose described. 55

6. The combination with a wall safe or receptacle, of a removable door-casing secured thereto, said casing having an annular flange or projection around its outer edge.

7. The combination with a wall safe or receptacle, of a removable door-casing adjustably secured thereto, said casing projecting beyond the surface of the wall of the safe, for the purpose described. 65

8. The combination with a wall safe or receptacle having an opening formed therein, a door-casing having an annular flange or projection around its outer edge, and means for adjustably securing said casing in said opening. 70

9. The combination with a wall safe or receptacle having a circular opening, the wall surrounding the opening being stepped to form a seat for a door-casing, a door-casing adapted to fit said seat, said casing being provided with an annular flange around its outer edge, and screws passing from the inside of the receptacle through the wall surrounding the opening and into the casing for adjustably securing the latter to the receptacle. 80

In testimony whereof I have hereunto set my hand in presence of two subscribing witnesses.

HARVEY C. LOWRIE.
